UNITED STATES PATENT OFFICE.

CARL W. FIEGE, OF HEALDSBURG, CALIFORNIA.

DEHYDRATOR.

Application filed September 27, 1923. Serial No. 665,208.

To all whom it may concern:

Be it known that I, CARL W. FIEGE, a citizen of the United States, residing at Healdsburg, in the county of Sonoma and State of California, have invented certain new and useful Improvements in Dehydrators; and I do hereby declare the following to be a full, clear, and exact description of the invention, such as will enable others skilled in the art to which it appertains to make and use the same.

This invention relates to a dehydrator.

The prime object is to provide a more efficient plant or apparatus of this character which is simple, durable and comparatively inexpensive in construction and which dispenses with the necessity of employing upper decks or long return air ducts.

Another object is to provide a construction in which the material in its passage will be subjected to alternate currents of heated air traveling in opposite directions.

Another object is to provide a construction in which the space beneath the cars used to contain the material to be dried, may be utilized as a return duct for the air.

A further object is to provide a construction using radiators to heat the air, and supporting means for the radiators in connection with sealing means for engagement with the car, to insure passage of the air along the proper courses.

Another object is to provide a construction in which the air is supplied through the apparatus in two separate streams or currents in combination with a car or other body containing the material to be dried, adapted to be subjected to the action of one current and then to the action of the other current.

Another object is to provide a construction in which the air travels in a tortuous path through the car, in connection with a particular construction of the car wherein it is subdivided to render such passage practical.

Various additional objects and advantages will become apparent from the description following taken in connection with accompanying drawings illustrating an operative embodiment.

In said drawings:

Figure 1 is a horizontal sectional view through the improved apparatus;

Figure 2 is a fragmentary horizontal

sectional view taken on line 2--2 of Figure 3;

Figure 3 is a transverse sectional view taken on the line 3--3 of Figure 1; 60

Figure 4 is a longitudinal sectional view taken on the line 4--4 of Figure 3;

Figure 5 is a longitudinal sectional view taken on the line 5--5 of Figure 3;

Figure 6 is a plan view of the blower; 65

Figure 7 is a detail vertical sectional view through the car or drying rack;

Figure 8 is a detail view of one of the trays employed;

Figure 9 is a sectional view taken on the vertical plane indicated by the line 9--9 of Figure 1, and 70

Figure 10 is a sectional view taken on the vertical plane indicated by the line 10--10 of Figure 9. 75

In carrying out the invention, a housing or tunnel 10 of any suitable construction and length is provided having double railway tracks rails 11 running therethrough and on the floor 12 thereof. An entrance door 13 is hinged to one end of the housing as at 14 and an outlet door 15 is hinged to the other end of the housing as at 16. 80

Suitable bars or racks 17 are adapted to enter the housing 10 through the way covered by door 13 and to leave the housing through the way covered by door 15. These bars or racks may be square as shown or of any desired shape and be provided with wheels as at 18 whereby they may travel 85 along the track 11.

Side track 19 may be provided and have a truck 20 adapted to travel along the same on wheels 21. This truck carries short rail sections 11^a which are adapted to align with and normally form parts of the track rails 11. It will be seen that the sections 11^a are of such length that they completely accommodate one of the cars or racks 17 thereon so that the same may be removed from the track 11 by moving the truck 20 outwardly of the housing through a way 22 normally covered by a door 23 hinged to the housing as at 24. 95

Material to be hydrated is carried by cars or racks 17 which may be of any suitable construction, preferably having removable trays 24^a of flat construction secured together in any manner so as to secure maximum strength. One end of each car carries a removable end wall 25 detachably held in place as by pegs 26 removably dis- 100
105
110

posed in openings 27 in the floors 28 of the cars and by means of detachable bolts or other fastenings as at 29.

The blower casing 30 is set up in a housing 38 that may form part of the housing 10 and said casing 30 is in communication with the interior of housing 10 through divergent non-communicating ducts 31. In the casing 20, a suitable blower 32 is carried by a shaft 33 suitably journaled in the casing 30 and adapted to be driven in any suitable manner as through the medium of a belt or the like driven from an engine or source of supply and trained over a pulley 34 on the shaft 33. The blower 32 has a central partition 35 and its vanes 36 on opposite sides of said partition. The vanes thus force the air into the ducts 31 and the partition 35 prevents the air traversing from one side of the blower to the other side thereof, to the end that independent streams or currents of air may be blown or forced through the ducts 31. Housing 30 has air intake ducts 37 at the sides thereof which communicate by means of chambers 64 with return ducts 62 within the housing 10. The partition wall between housings 38 and 10 have outlet openings or ports 39 connecting the interiors of said housings. The ports 39 are normally closed by closure plates 40 hinged in place as at 41 and held in place by springs 42 associated with rods 43 and the tension of which springs is adapted to be varied through the manipulation of nuts or the like 44 on the rods or bolts 43.

Leading from each duct 31 is a moist air exhaust duct 45 in communication with the atmosphere under control of a closure plate or damper 46 pivotally mounted within the casing 10 at 47 and being under the control of an operating mechanism 48 which is capable of adjustment to dispose the damper 46 in different extents of opening.

The sizes of the cars or racks 17 is so proportioned with respect to the casing 10 that when the cars are positioned within the casing, the air will be blown as aforesaid in distinct currents from the blower on opposite sides of its partition and take a tortuous course, one current being in the direction of the arrows 50 and the other being in the direction of the arrows 51. Thus each current of air passes transversely of one of the racks 17 in one direction and then transversely through the next rack in the opposite direction and then through the next rack in the first mentioned direction etc., that is through the cars in alternate directions, and on each side of the blower. Suitable means, of course, is provided to coact with the casing and bars to form the necessary ducts for travel of the air in the line of the arrows. The roof of the casing 10 is designated 53 and supported as by means of uprights 54, a distance apart but sub-

stantially similar to the length of each car. Uprights 54 rise from longitudinal rails or ribs 55 disposed on opposite sides of the rails 11 and which form stands to support the heating coils 56. The coils 56 may consist of separate coils, under separate control and which may be heated in any suitable manner, for instance by steam or hot water or in lieu of the coils, any other heating means may be used. These heating coils are arranged in the line of travel of the air currents and may be less in number adjacent the entrance door 13 so that the material will be gradually heated as it advances through the housing.

The bottoms and walls 25 of the cars are imperforate or air proof and sealing strips 57 of rubber or other flexible material are vertically disposed, being carried by the uprights 54 and adapted to engage the walls 25. In addition, similar rubber or other sealing strips 58 are carried by the ribs 55 and adapted at their free ends to engage the sides of the cars. Likewise sealing strips of rubber or the like as at 59 may depend from the roof 53 and engage the walls 25. Sealing doors 60 of any suitable construction are hinged as at 61 to and within the housing 10 and adapted to engage the appropriate uprights 54 and the top and bottom walls of the housing in an air tight manner, being provided with gaskets or other means to accomplish this end. These doors are adapted to swing in the direction of the arrows applied to them.

That portion of the rib 55 which crosses the side tracks 19 is designated 55^a and is slidably removable from the adjacent portions of that rib. The section 55^a carries a sealing flap 55^b which is part of the adjacent sealing flap 58 and functions to close the space beneath the car in line with the side tracks 19. Handles 55^c may be connected to sections 55^a to facilitate its removal and replacement.

The air return duct is provided below the cars and between the cars and the bottom wall of the housing 10 and between the ribs 55 and sealing strips or flaps 58. This return duct is specifically identified as at 62. In order that the air from the end cars may enter such ducts 62, the sealing flap 58 at its ends on the appropriate side may be shortened or cut away in order to provide entrances as at 63.

From duct or passage way 62 the air returns to the blower through ducts or passageways 64. In operation, with power applied to the pulley 34, the shaft 33 will rotate and thus operate the blower 32 which will circulate the air through the housing from the duct 31, in the direction of the arrows; the duct 62 and duct 64 back to the blower. The coils at 56 are properly heated and thus the air as it passes over the coils

is heated and the dehydrating effect is imparted to the contents of trays 24 of the rack or cars 17. The ducts are maintained sufficiently airtight for the passage of the air in the manner stated in view of the various closure flaps, doors 60, and ribs 55. It will be realized that during operation, the air will become moist with water due to extractions of moisture from the contents of the trays 24. This moisture laden air will be permitted to escape to the atmosphere by adjustment of the dampers 46. This will cause a sub-atmospheric condition within the housing 10 and this condition will cause the dampers or closures 40 to open automatically to permit sufficient fresh air entering housing 10 to restore the supply of air, said dampers being closed by spring 42 when the pressure within housing 10 and the tension of the springs is sufficient to do so. The dampers are controlled so as to open to the predetermined degree through the adjustment of the nuts 44 which vary the tension of the springs 42. Should it be desired to remove a car or cars before the same reaches the discharge opening of door 15, such car may be moved onto the truck 20 and the truck then operated along the track 19. The cars are of such size that they may be preferably manually pushed or shoved one against the other and advanced in this way. Also, as the cars advance to the dehydrator or housing 10, they are permitted to remain stationary therein for any suitable interval or period of time and that as they advance, and the foremost car passes out of the housing, the air will travel through the cars in opposite directions, that is the cars advance in a step by step manner and at the alternate steps, the passage of the air through the cars is in opposite direction. It will be noted that the heating of the housing is greatest adjacent the outlet end thereof since a heater is omitted adjacent the inlet door. In this way, the cars as they pass through housing 10 are gradually heated and the intensity of the heat is greatest at the discharge end.

Various changes may be resorted to provided they fall within the spirit and scope of the invention.

I claim as my invention:—

1. In a dehydrator, means to cause air to pass over the material and substantially in a horizontally direction, means to carry the material, and means to form a return passage for the air to the first mentioned means under the entire length of said means to carry the material.

2. In a dehydrator, movable means to carry the material, means to cause the air to travel through the material, and means coating with said movable means to form a return passageway below said material and substantially throughout the length of

the movable means to the first mentioned means.

3. In a dehydrator, movable means to carry the material, means to cause travel of the air through the material, and means co-acting with the movable means adjacent the base thereof and substantially throughout the length thereof to form a return passageway for the air to the first mentioned means below the movable means. 75

4. In a dehydrator, means to carry the material, a blower to force air through the material, means forming a return passageway to the blower between the bottom of the second mentioned means substantially 80 throughout the length thereof and the bottom of the dehydrator.

5. In a dehydrator, movable means to carry the material, means to cause travel of the air through the material, means co-acting with the movable means adjacent the base thereof to form a return passageway for the air to the first mentioned means below the movable means, and heating means 85 over which the air passes. 90

6. In a dehydrator, cars to carry the material, a housing in which the cars move, ribs rising from the base wall of the housing on opposite sides of the cars, sealing means between said ribs and the cars to form a 95 passageway beneath all of the cars, means to supply air through the material, the latter means being in communication with the passageway so that the latter will serve as a return. 100

7. In a dehydrator, cars to carry the material, a housing in which the cars move, ribs rising from the base wall of the housing on opposite sides of the cars, sealing means between said ribs and the cars to form a 105 passageway beneath all of the cars, means to supply air through the material, the latter means being in communication with the passageway so that the latter will serve as a return, and heaters supported by said 110 ribs.

8. In a dehydrator, cars to carry the material, a housing in which the cars move, ribs rising from the base wall of the housing on opposite sides of the cars, sealing means between said ribs and the cars to form a passageway beneath all of the cars, means to supply air through the material, the latter means being in communication with the passageway so that the latter will serve as a return, uprights rising from said ribs, and doors coating with certain of said uprights and the side walls of the housing. 115

9. In a dehydrator, cars to carry the material, a housing in which the cars move, ribs rising from the base wall of the housing on opposite sides of the cars, sealing means between said ribs and the cars to form a passageway beneath all of the cars, means to supply air through the material, the lat- 120 125 130

- for means being in contact with said material, a passage-way, a return air duct, a means for a return, special air ducts, and doors, a door coating with carbon, a heating coil, a heater means heated by a gas, and an intermediate certain of said caravans.
10. In a dehydrator, a housing, a means to carry the material through the housing, said caravans having a heating coil, a heating coil being in contact with the walls to prevent the walls from becoming cold, a means to carry the material through the housing, a means to carry the material through the housing, doors extending from the side walls, 15 to certain of said walls, a return pipe extending from the side walls, a heating coil being in contact with the walls, the structure thus forming a tortuous passage for the material, the housing, 20 the housing and toward opposite ends thereof, said means being in contact with the heating coil with the blower.
11. In a dehydrator, a housing, a means to carry the material through the housing, a blower, and means directing said material to a current of air from the blower, the housing and toward opposite ends thereof, 25 said means being in contact with the heating coil with the blower, a blower to circulate air throughout, an exhaust means in communication with the air passage, an automatic valve, and a supply means for supply of air to the air passage, consisting of a chamber 30 in communication with the atmosphere, a valve, and a normally closing communication between the said chamber and passage, an expandable diaphragm spring for said damper, the said diaphragm spring being subject to a vacuum 35 between the passage and the atmosphere.
12. In a dehydrator, a housing for the material, an entrance door at one end of the housing, an exit door at the other end of the housing, a blower associated with the housing and adapted to direct air in two opposite currents in a tortuous passage formed in points intermediate the doors and toward the respective doors.

40 In testimony whereof I affix my signature in presence of two witnesses,

CARL W. KIEGE
